UNITED STATES PATENT OFFICE.

BENJAMIN F. KELLEY, OF TULSA, OKLAHOMA.

CASING SPIDER AND SLIPS.

1,405,223.

Specification of Letters Patent. Patented Jan. 31, 1922.

Application filed December 27, 1920. Serial No. 433,468.

To all whom it may concern:

Be it known that I, BENJAMIN FRANKLIN KELLEY, a citizen of the United States, residing at Tulsa, in the county of Tulsa and State of Oklahoma, have invented new and useful Improvements in Casing Spiders and Slips, of which the following is a specification.

My present invention pertains to that 10 class of devices known as casing spiders and slips, and which are used extensively in oil and water well boring operations, for preventing the slipping of the casing in the lowering of said casing, and to also hold 15 the casing sections when being coupled. Such devices are also used in connection with hydraulic jacks or analogous means which pull the casing from the well, to hold the casing against slipping when new 20 grips are to be obtained thereon.

It is the object of this invention to simplify and improve the existing art by producing a mechanism wherein the slips are positively guided to casing engagement and 25 are automatically brought to release position by means associated with and operated by the main pull line when the latter is in taut condition by the weight of the casing to which it is hitched.

It is a further object to produce in a casing spider and slip, weighted means for influencing the slips to casing engaging position, guide means for said slips, swinging means for bringing the slips to casing release 30 position, automatic means influenced by the pipe lowering means for influencing the swinging and weighted means to retain the slips in release position, and manually operated means for influencing the swinging 35 means to permit of the slips engaging the casing to hold the same, regardless of the taut condition of the casing lowering means.

The invention further resides in the novel 40 construction, combination and operative arrangement of parts.

The foregoing, and other objects which will appear as the nature of the invention is better understood, may be accomplished by 45 a construction, combination and association of elements such as is disclosed by the drawings which accompany and which form part of this application.

In the drawings:

Figure 1 is an elevation of the improvement arranged in gripping position with a well casing, parts being in section, and parts being broken away.

Figure 2 is a greatly enlarged sectional view on the line 2-2 of Figure 1, looking 60 downward.

Figure 3 is a sectional view on the line 3-3 of Figure 2.

Figure 4 is a detail sectional view on the line 4-4 of Figure 2.

Figure 5 is a side elevation of the guide housing.

Figure 6 is a plan view showing the arrangement of the slips when associated.

Figure 7 is a plan view of the spider.

Resting on suitable beams 1 is a spider 2 that constitutes one of the elements of the improvement. The spider has at diametrically opposed points outstanding lugs 3 to which are pivotally secured bails 4, where 75 by the device may be handled. For lessening the weight of the spider, the lugs preferably have their upper faces centrally depressed or grooved longitudinally.

The spider has its cylindrical bore 5 80 flared inwardly from the top to the bottom thereof, and in the said bore there is a liner 6 that has its outer surface resting on the bore 5 and flared complementary with the flared bore of the said spider. The bore of 85 the liner 6 is also flared from the top to the bottom thereof, the said bore being indicated by the numeral 7. Preferably the liner slightly increases in thickness from the upper to the lower end thereof, and its said 90 lower end is beveled or flared inwardly, as at 8 to the bore 7.

Screwed in suitable openings which are arranged at diametrically opposed points on the upper face of the spider and which are 95 arranged right angularly with respect to the projecting lugs 3 of the said spider, are guide pins 9 for the lifting ring 10 of the improvement.

Received in the lifting ring 10, and bolted, 100 as at 11, to the upper face of the spider 2 is a guide housing 12. The guide housing is in the form of an inverted cup-shaped member including a flat base 13 that is flanged both inwardly and outwardly with 105 respect to the tubular body 14 of the guide

housing. The tubular body has spaced openings therethrough, and the portions 15 provided between the openings are reinforced, on their outer faces by ribs 16. The 5 annular top of the guide housing is indicated by the numeral 17, and the central opening therethrough has its walls, from the top and bottom edges thereof flared inwardly, as at 18 and 19 respectively. The 10 web portions 15, provided between the openings in the body of the guide housing have their upper portions extending angularly to the annular or ring-shaped top of the housing, and each of these portions has an 15 integral tubular boss 20 thereon which is connected to the ribs 16 and to the top of the housing. Each of the bosses has its bore 21 arranged at an inward angle with respect to the guide housing, and through 20 each of the said bores there is arranged for slidable movement a guide pin 22 that has its lower end threaded and screwed in threaded openings in the widened top portions of the respective casing slips 23. As 25 disclosed in Figure 6 of the drawings, four casing slips are employed. Each of the slips is segmental in plan, having its inner face toothed, as at 24 and its outer surface flared inwardly from the top to the bottom 30 thereof, as at 25. The flared surfaces 25 are complementary with the flared bore 7 of the liner 6, being disposed in contacting engagement with the said bore. By reference, especially to Figure 6 of the drawings, 35 it will be seen that the confronting ends of the casing slips are out of contacting engagement, and also that each of the slips, to the opposite sides of the threaded openings 26 that receive therein the angularly arranged guide pin 22, has additional or reduced threaded openings 27. In the pairs of openings 27 on each of the slips there are screwed eyes 28, which receive therethrough links 29, the said links being also connected 40 to eye bolts 30 that pass through openings and are secured by nuts 31, on inwardly directed ear portions 32 on the top flange of the lifting ring 10. By reference, especially to Figure 2 of the drawings, it will be seen 45 that the top flange of the lifting ring is scalloped from the inner edge thereof so that comparatively deep openings 33 are provided between the inwardly projecting portion which I have termed ears 32. Four 50 of the openings 33 are arranged to receive therethrough an angularly arranged guide pin of the casing slips. The lifting ring guide pins 9 pass through openings in enlargements or bosses 34 at diametrically opposed points on the ring outward of the 55 guide housing 12. The lifting ring 10 has its sides, in a line with the bosses 34, provided with outwardly projecting hub portions 35, to which are connected, as at 36 60 depending links 37. Each link 37 has its

body portion arranged at a slight outward angle, but its ends are straight, and the lower straight ends are pivotally connected, as at 38 to the sides of a spider lever 39. The spider lever is in the nature of a split 70 ring member, but has its sides to which the links are pivotally connected, straight. The ends 40 of the spider are also straight and are in parallelism, and are pivotally connected, as at 41 to the angle ends 42 of the 75 bracket 43. The bracket is bolted, as at 44, to one of the lugs 3 of the spider 2.

Through the center of the guide housing, the lifting ring and the bore of the liner 6, the well casing tube sections 45 are received. 80 The casing slips, being constructed of metal are comparatively weighty, but additional weight is imparted thereto by the lifting ring 10 which is substantially hingedly connected to the casing slips by the links 29, so 85 that the casing slips will be forced downwardly in alignment, and the toothed inner faces thereof will normally engage the casing 45 to hold the casing against downward movement. The teeth of the casing slips 90 comprise straight horizontal shoulders and angle walls between the shoulders, the angle walls being directed upwardly to permit of the upward movement of the casing 45. Such movement would, of course, slightly 95 move the casing slips in an upward direction. The casing slips are positively guided at a desired angle to bring the same away from the casing 45, through the medium of the pins 22, and the inflared portion at the 100 end of the bore of the liner 6 permits of a free passage of the casing sections 45 and their couplings 46 either in an upward or a downward direction. The lifting ring, being guided by the lifting ring guide pins 105 9 will also be raised in a perfectly horizontal position when an upward pressure is applied to the bail end of the spider lever 39.

A portion of the derrick floor, is indicated in Figure 1 of the drawings by the 110 numeral 45'. The derrick floor has an opening 46' therethrough for the casing sections 45 and their couplings 46. To one side of the openings 46' the floor 45' has another opening 47 in which is arranged guide pulleys 48 for a cable 49 that is secured, as at 50 to the spider lever 39. On the cable there is a stop collar 50'. Pivoted, as at 51, to a bracket on the under face of the floor 45', is a lever 52. This lever has an upset end 53 that passes through an opening 54 in the floor 45'. The angle end 53 of the lever is headed, as at 55. The lever is provided with a laterally extended or widened portion 56, having an opening through which 115 a cable 49 passes. The widened or eye portion 56 of the lever normally rests on the stop member 50' on the cable 49.

The upper end of the cable 49 is connected to one end of the helical spring 57. 130

To the opposite end of the spring there is a second cable 58 which is secured to a downwardly directed angularly disposed ear 59 on the upper end and at the lower corner of 5 a hollow substantially rectangular member 60. The corner of the member 60 diagonally opposed to that provided with the ear 59, has an upstanding ear 61 to which is connected a short rope or cable 61' that is 10 wound around and secured to the first girt 62 of the derrick, as indicated by the numeral 63. The member 60, adjacent to its lower end has journaled therein peripherally grooved guide wheels 64 for the main 15 pull line 65 that is connected to the ground pulley of the derrick (not shown). The line 65 is guided through the body of the member 60 under a grooved sheave 66 which is journaled at the upper corner of the said 20 member 60. The line 65 is hitched to one of the casing sections 45. The member 60 not only provides a guide for the pull line 65, but being hingedly supported by the element 61' on the girt 62, and being influenced to 25 an angular position by the spring 57 of the cables 49 and 58, serves as a control means for bringing the slips either into or out of casing gripping position.

When the member 60 is in angular position, as illustrated in Figure 1 of the drawings, the spring influenced cables connected to the spider member permit of the latter assuming its normal inactive position, the same resting on one of the lugs 3 of the spider. 30 Thus the weight influenced casing slips are moved downward in the liner so that they are in gripping engagement with the casing section 45. When the main pull line 65 is drawn taut, the member 60 will be swung 35 to vertical position along the side of the suspending element 61' therefor. This, of course, occurs when the main pull line 65 is in its straight and taut condition, and it is in such condition when supporting the casing sections for lowering the same into the 40 well. The swinging of the member 60 causes a pull on the spring influenced cable that is connected to the spider lever 39, swinging the latter upon its pivots 41, causing the same through the medium of the 45 links 17 to move in an even upward vertical direction the lifting ring 10 which latter, by its link connection with the casing slips, will move the latter out of casing engaging position. Thus the casing may be lowered in 50 the well. In a like manner, by reversing the movement of the pull line 65, the casing may be withdrawn from the well. Should the pull line become broken, the member 60, 55 through the medium of the spring connecting the cables for the spider lever will be again swung to the position illustrated in Figure 1 of the drawings, slackening the last mentioned cables and permitting the spider 60 lever to drop by gravity and carry therewith

the ring 10 and the casing slips 23, the latter being forced in pipe engaging position by the link connection between the same and the lifting ring 10, but are, as previously stated, properly guided by the pins 22. Again, 70 when the pull line 65 is taut and the member 60 swung to vertical position, should it be found desirable to prevent the lowering of the casing in the well, pressure is applied to the headed end 55 of the lever 52 which, having its eye portion 56 engaging with the contact member 50' on the cable 49 will expand the spring 57, slackening the portion of the said cable below the stop 50', permitting the spider lever, ring and casing slips to swing 75 or gravitate downwardly so that the casing slips will be brought into casing gripping position.

It is believed that the foregoing description, when taken in connection with the drawings will fully set forth the simplicity and advantages of the improvement to those skilled in the art to which such inventions relate so that a further detailed description is not considered necessary. It is considered, 85 however, necessary to state that the drawings and description refer to a satisfactory embodiment of the improvement as it now appears to me, and that I may at a later date, make such changes therefrom as fall within 90 the scope of what is claimed.

Having described the invention, I claim:

1. In an apparatus of the class described, the combination of a casing to be lowered or raised, casing slips normally engaging the casing, guide means therefor, weighted means associated with each other, and with the slips for retaining the slips in casing engaging position, flexible operating means for said last mentioned means, a pivotally supported member connected with said flexible means and normally retained by the latter in an angular position, a pull line guided through said member and hitched to the casing, operating means for the pull line, and said pull line, when drawn taut by the operating means and the weight of the casing to which it is hitched, adapted to swing the pivoted member in an upward direction to draw on the flexible means to operate the means associated therewith and bring the slips to non-casing engaging position.

2. In an apparatus of the class described, a casing to be raised or lowered, weighted toothed slips normally engaging the casing, a pull line hitched to the casing, operating means therefor, pivoted means engaging the pull line for sustaining a portion thereof at an angle when the operating means for the pull line has been halted and the pull line slackened, means for moving the slips to non-casing engaging position, and operating means between said last mentioned means and said pivoted means whereby, when the pull line is drawn taut and the said piv-

oted means is moved thereby to an upward and substantially vertical position, to influence the last mentioned means to actuate the slip operating means and bring said slips 5 to non-casing engaging position.

3. In an apparatus of the class described, a well casing to be raised or lowered, a spider, slips therein normally engaging the casing for holding the casing against movement in a downward direction and for permitting movement of the casing in an upward direction, means influencing the slips for bringing the same to casing engaging position, a pull line hitched to the casing, 10 a pivotally supported member through which the pull line is guided, means connected to said member and the slip influencing means for causing the said member to assume an angular position when the pull line is taut or broken and to also cause the slips to engage with the casing, and said pivoted member adapted when the pull line is drawn taut to be swung substantially vertically and draw upon the operating 15 means for the slip influencing means to actuate the latter and bring the slips out of casing engagement.

4. In an apparatus of the class described, a well casing to be raised or lowered, a spider surrounding the casing, slidable slips therein normally contacting the casing for holding the same against outward but permitting an upward movement thereof, weighted means influencing the slips for bringing the latter to casing engaging position, a pull line hitched to the casing, operating means therefor, a pivotally suspended member through which the pull line is guided, a spring influenced flexible element connected between the weighted slip influencing means and said member, a stop on the flexible member below the spring means associated therewith, a pivotally supported lever having an eye portion through which the flexible member passes, and said lever having its eye normally resting on the stop, the guide member for the pull cable designed, when the cable is drawn taut to be swung upon its pivot to draw on the spring influenced flexible element to cause the latter to actuate the slips influencing means and bring the slips out of casing engagement, and the said lever, when actuated, designed to expand the spring of the flexible member to slacken the portion thereof below the stop to permit of the slip influencing means to bring the slips to casing engaging position.

5. In an apparatus of the class described, 60 the combination with a well casing to be raised or lowered, weighted casing slips engaging the casing, directing means therefor, guide means for the slips, means movable toward and away from the slips loosely associated with said slips, swinging means

connected with said movable means, flexible spring influenced operating means for the swinging means, pivotally supported means connected to said flexible means, and normally retained at an angular position by 70 said flexible means, a pull line guided through the pivoted means and hitched to the casing, operating means therefor designed to draw the pull line taut and to move the pivotally supported means to a 75 position to draw on the flexible means to influence the swinging and movable means to bring the slips to non-casing engaging position.

6. In an apparatus of the class described, 80 the combination with a well casing to be raised or lowered, weighted casing slips engaging the casing, directing means therefor, guide means for the slips, means movable toward and away from the slips loosely 85 associated with said slips, swinging means connected with said movable means, flexible spring influenced operating means for the swinging means, pivotally supported means connected to said flexible means, and normally retained at an angular position by 90 said flexible means, a pull line guided through the pivoted means and hitched to the casing, operating means therefor designed to draw the pull line taut and to 95 move the pivotally supported means to a position to draw on the flexible means to influence the swinging and movable means to bring the slips to non-casing engaging position, and manually operated means engaging an element on said flexible means for permitting the slackening of said flexible means below said element to permit of the means associated with the slips for returning the latter to casing engaging position 100 regardless of the tightening or slackening on the pull line.

7. In an apparatus of the class described, a spider having a downwardly tapering opening, a tapered liner therein having its 110 lower end flared inwardly toward the reduced portion of the bore thereof, a well casing section to be raised or lowered passing through the liner, casing slips comprising spaced segmental members having 115 their inner faces formed with transverse teeth, and their outer surfaces tapered to engage with the tapered bore of the liner, a guide housing secured on the spider, a lifting ring surrounding the guide housing, 120 guide pins between the spider and the guide ring, angularly arranged guide pins between the respective slips and the guide housing, pivoted links between the lifting ring and the respective casing slips, a spider lever 125 comprising a split ring member which has its ends pivotally connected to the spider, a pivoted link connection between the sides of the spider lever and the lifting ring, a divided cable having one of its ends secured 130

to the spider lever, a spring connecting the confronting ends of the cable, a pivotally supported guide member to which the opposite end of the cable is connected, a stop 5 on the lower cable member, a pivotally supported lever engaging said stop, a pull line guided through the pivoted member

and hitched to the pipe casing, and operating means for said guide line, all as and for the purpose set forth. 10

In testimony whereof I affix my signature.

BENJAMIN F. KELLEY.
